UNITED STATES PATENT OFFICE.

SARAH EMELINE BOWSER, OF MUFF, PENNSYLVANIA.

VIOLIN-BOW.

SPECIFICATION forming part of Letters Patent No. 613,897, dated November 8, 1898.

Application filed December 31, 1897. Serial No. 665,012. (No model.)

To all whom it may concern:

Be it known that I, SARAH EMELINE BOWSER, residing at Muff, in the county of Armstrong and State of Pennsylvania, have invented a 5 new and useful Violin-Bow, of which the following is a specification.

This invention relates to improvements in violin-bows; and the object thereof is to provide a folding bow which may be quickly and 10 readily folded to convenient size when not in use, so as to enable a smaller violin-case to be used than is now required to accommodate the ordinary bow.

With the above object in view the invention 15 consists of a bow having the body thereof formed in sections, said sections having their meeting ends hinged together and formed with a shouldered lap-joint, the sections being also screw-threaded to receive a screw-threaded sleeve which is adapted to hold said 20 sections in alinement when it is desired to use the bow.

The invention further consists in the improved construction, arrangement, and combination of parts hereinafter fully described and afterward specifically pointed out in the 25 claims.

In order to enable others skilled in the art 30 to which my invention most nearly appertains to make and use the same, I will now proceed to describe its construction and operation, having reference to the accompanying drawings, forming part of this specification, in which—

35 Figure 1 is an elevation of a violin-bow constructed in accordance with my invention. Fig. 2 is a similar view showing the same folded. Fig. 3 is an enlarged vertical longitudinal sectional view of Fig. 1. Fig. 4 is an 40 enlarged view of the body of the bow, showing the same in elevation, with the sleeve removed from the joint and the sections slightly separated.

Like letters of reference mark the same 45 parts wherever they occur in the various figures of the drawings.

The body of the bow is composed of the sections A and B, section B being somewhat longer than section A, said sections being 50 hinged together at C and having their meeting ends reduced, as illustrated at D, said re-

duced ends adapted to overlap when the bow-sections are in alinement, thus forming a shouldered lap-joint. The sections are screw-threaded at their meeting ends, as illustrated 55 at E, the screw-threads on section A extending rearward from the end thereof a greater distance than those upon section B to receive the sleeve F, which is interiorly screw-threaded and provided with the annular exterior enlargement G, which is milled, so as to be readily engaged by the fingers for rotating the sleeve. This sleeve is adapted to be adjusted to cover the joint, as illustrated in Fig. 3, and thus hold the sections in alinement. 60

When it is desired to fold the bow, all that is necessary is to rotate the sleeve to uncover the joint, when the smaller section A may be swung inward against the under side of section B, as illustrated in Fig. 2. Thus the bow is folded to convenient length and a smaller violin-casing may be used than is now the case with the ordinary bow. The ordinary violin-case is made considerably longer than 75 the violin in order to accommodate the bow. With my improved folding bow the case may be shortened, and thus be more convenient to carry.

While I have illustrated and described the 80 best means now known to me for carrying out my invention, I do not wish to be understood as restricting myself to the exact details of construction shown and described, but hold that any slight changes or variations, such as 85 might suggest themselves to the ordinary mechanic, will properly fall within the limit and scope of my invention.

Having thus fully described my invention, what I claim as new, and desire to secure by 90 Letters Patent of the United States, is—

1. A violin-bow having the body thereof formed of sections hinged together, and means for holding said sections in alinement, substantially as described. 95
2. A violin-bow having the body thereof formed of sections hinged together and having their meeting ends so formed as to provide a shouldered lap-joint when the sections are in alinement, and means for holding said sections in alinement, substantially as described. 100

3. A violin-bow having the body thereof formed of sections hinged together and having a shouldered lap-joint at their meeting ends, said meeting ends being exteriorly threaded, and an interiorly-threaded sleeve carried by one of said sections and adapted to be moved to cover the joint and hold the

sections in alinement, substantially as described.

SARAH EMELINE BOWSER.
